MACHINERY SUPPORTS

Jerome J. Sloyan, Trenton, N. J.

Application March 8, 1955, Serial No. 492,944

8 Claims. (Cl. 308—3)

This invention relates to supports, and more particularly to that type of support for motors or other machinery for providing a movable carriage by which the motor or the like has adjustable relation to some other instrumentality.

In most instances, prior art supports of this general character have failed in numerous respects to adequately fulfill trade requirements, such as easy sliding with extensive metal-to-metal surfaces, low cost promoted by use of standard materials, elimination of chatter, simplicity, compactness, rigidity, and so forth.

The present invention accordingly proposes a construction of support overcoming the criticisms and inadequacies of the prior art.

More specifically, the invention proposes a practical construction providing slidably fitting gliders on rails with extensive metal-to-metal surface engagement both longitudinally and circumferentially.

In addition to the foregoing object, the invention further purposed to compensate for discrepancies of alignment and parallelism.

Another object of the invention is to obtain a strong structure which will not become deformed in use.

A further object is to provide cushioning means in the glider.

Other objects, advantages and novelty of construction will appear to persons skilled in the art to which the invention appertains as the description proceeds, both by direct recitation thereof and by implication from the context.

Referring to the accompanying drawings, in which like numerals of reference indicate similar parts throughout the several views;

Figure 1 is a side elevation of the support of this invention in use;

Figure 2 is a plan of the support, partially broken away;

Figure 3 is a longitudinal sectional view on line III—III of Fig. 2;

Figure 4 is a longitudinal sectional view on line IV—IV of Fig. 2;

Figure 5 is a cross-sectional view on line V—V of Fig. 3;

Figure 6 is a cross-sectional view on line VI—VI of Fig. 7 showing reenforcement by means of truss-bracing;

Figure 7 is a plan of the construction of Fig. 6;

Figure 8 is a view similar to Fig. 6, but showing a plurality of tubular housings and a one-piece truss-bracing;

Figure 9 is a perspective cross-sectional view of a modified construction, taken on a line corresponding to line VI—VI of Fig. 7;

Figure 10 is a cross-sectional view of another modified construction, taken on a line corresponding to V—V of Fig. 3;

Figure 11 is a longitudinal section of another modified construction, taken on a line corresponding to III—III of Fig. 2; and together with Fig. 10, forming part of the invention.

Figure 12 is a cross-section on line XII—XII of Fig. 11; and

Figure 13 is a perspective sectional view on line XIII—XIII of Fig. 11.

For preliminary clarification to orient the present invention in relation to its use, it may be pointed out that the support constituting my improvement has particular utility in connection with belt driving of one machine by another, and may be utilized either to support the driving unit or the driven unit. Arbitrarily, therefore, Figure 1 shows a motor 30 which drives an instrumentality 31 through the agency of a belt 32 and pulleys 33 and 34 respectively on the shafts of said motor and instrumentality. The support has basic construction enabling it to be readily used with machines wherein one is equipped with a variable pitch pulley or with machines wherein both are equipped with pulleys having fixed diameters. In the first instance, the operator moves the machine carried by the support, which in this showing is the motor, and in so doing changes the effective pitch diameter where the belt engages the pulley and thereby changes the speed of the driven machine. In the second instance mentioned, the operator adjusts the belt tension initially, and thereafter the tension is maintained by spring loading in the support. The side elevation of Figure 1 is correct for either such use of the support, whereas in such other views as Figs. 2 and 4, spring loading is illustrated as being utilized. The construction is such that a user may employ the support for one type of drive, but if he later desires to use the support for the other type of drive, may, without difficulty, make the appropriate alteration of the support and thereby avoid the need of discarding one and obtaining another to fulfill the new requirement. Such universality or adaptability to either positive or spring-loaded actuation is of importance to many users.

An essential feature of the present invention resides in the construction of a support 35 for the piece of machinery, which is herein exemplified as motor 30. As shown, a bed 36 is provided to which the instrumentality 31 is secured, and to which a fixed portion of the support of the present invention is secured, it being understood that said bed is representative of any structure, such as floor, table, wall, shelf, ceiling, or the like which will afford relatively fixed mounting for the aforementioned instrumentality and for the fixed portion of the support.

The fixed portion of the support as herein illustrated, comprises two parallel rails 37 the ends of which are made fast to transverse cleats 38 which may conveniently be formed from appropriate lengths of angle iron one flange of which forms a foot juxtaposed to and adapted to be secured to bed 36 and the other flange of which stands perpendicularly and constitutes an end abutment and rigid mounting for the said rails. The assembly of rails and cleats forms a rectangle of which the cleats will arbitrarily be referred to as at the ends and the rails as at the sides of the rectangular assembly constituting the fixed or basal portion of said support. Cylindrical steel rods of precise diameter and smooth outer surfaces are available on the market, and for economical manufacture and efficiency of operation, I provide a construction of support enabling me to utilize such rods as the rails 37 only necessitating cutting the rods to proper length and appropriately machining the extremities for retention thereof in the cleats as by threading the reduced ends and applying nuts 37' thereon where projecting through said cleats.

The movable portion of the support comprises a carriage 39 having slidable movement longitudinally of the rails, said carriage having gliders 40 at its opposite side margins cooperating with the rails to not only pro-

vide for sliding of the carriage on the rails, but to also keep the carriage assembled upon the rails no matter in what position the support may be located.

Each glider is conveniently comprised of rectangular tubing, stock sizes of which are available on the market, and in the present showing said tubing is square in cross-section having an inside dimension materially greater than the outside dimension or diameter of the rail. In the region proximate to each end of the rectangular tubing of the glider and within said tubing, is a bearing assembly 45 consisting of a metallic bushing 46 slidably fitting the rail, and a resilient annulus 47 on the bushing, said annulus having a metallic cylinder segment 48 in arcuate contact therewith and making line contact with the inside of the rectangular tubing of the glider. As shown in Fig. 5, for instance, said segment 48 is C-shape in cross section in its preferred embodiment.

In the fabrication of the preferred construction, the initial outside diameter of the segment 48 is approximately equal to the distance between opposite inside faces of the glider tube and the outside diameter of the annulus is equal to the inside diameter of the segment, but the inside diameter of said annulus is slightly smaller than the outside diameter of the bushing 46. Hence, when the resilient annulus 47 is applied on the bushing, it is stretched somewhat and its outside diameter tends to increase thereby tending to expand the C-shaped segment. A compressive force consequently, in this instance, has to be exerted on the segment to reduce its diameter in order to insert the assembly 45 into the glider tube. That compression results in a deformation of the resilient annulus 47 at the circumferential part thereof not confined by the metallic segment 48, and that deformation suffices to cause the resilient annulus to protrude at its unconfined portion into contact with the adjacent wall of the glider tube.

I wish it to be understood that the invention is not confined to provision of protrusion of the annulus, as it is also contemplated that there may be no deformation of said annulus either when applying it to the bushing 46 or when inserting the assembly 45 into the glider tube. In that case, there would then be a void or clearance between the periphery of the annulus and the proximate wall of the glider tube equal at their nearest approach to the thickness of the segment material.

However, by virtue of the resiliency of the annulus 47, the amount of the clearance can be controlled by predetermined choice of inside and outside diameters of the resilient annulus and by the thickness of the segment employed. In fact, by making appropriate choice of dimensions, I am enabled to selectively provide a predetermined clearance, no clearance, or a state of compression of the annulus against the glider tube wall. To what extent there will be clearance, no clearance or compression, is a matter to be determined by the requirements of the installation where used. In any event, the various components would be suitably proportioned to safely support the load to which the assembly is likely to be subjected.

In all constructions herein shown, assembly 45 travels with the glider but without rigid attachment thereto. Suitable anchoring means 50 is accordingly provided between said assembly and glider which affords a restricted mobility of lateral location sufficient to enable the assembly to adjust itself within the glider tube and more especially to adjust itself in a direction transverse to said tube. Thus, should the distance between center lines of the two glider tubes differ slightly from the distance between the axes of the rails, the lateral mobility or lost motion provided by said anchoring means enables the bearing assembly 45 to be self-aligning coaxially with the rail and be slightly offset from central position within the glider tube. In Figures 2, 5, 12 and 13, the anchoring means 50 is illustrated as a rivet or the like sweated in

or otherwise made fast to the glider tube and projecting into a hole 51 of slightly greater size than the shank of the rivet, said hole being formed in the bearing assembly to loosely receive said shank of the rivet. In Figures 9 and 10, the anchoring means is illustrated as a screw fixed in the bearing assembly with hole 51 provided in the glider tube thereby affording the desired looseness or lost motion.

It is opportune to point out that whereas in most instances the rails are each shown with an individual glider therefor, the invention contemplates inclusion of both rails within a single oblong glider that embraces both rails as shown in Fig. 9. This construction is accomplished by providing a top plate 52 that spans the two rails, bends down at the outsides of the two rails to form side walls 53 for the glider, then bends under the rails to form a bottom wall 54 beneath each rail in conjunction with a bottom plate 55 welded or otherwise made an integral part of the common glider.

Furthermore, it may be pointed out that whereas in most instances the confining segment 48 for the resilient annulus 47 of bearing assembly 45 is C-shaped so as to be substantially tangential to three walls of a square tube, variations thereof are contemplated. For instance, in Fig. 9, while the segment is C-shaped, it has tangential status with only the top and bottom walls of the glider and is held loosely in the glider by anchoring means in the upper wall of the glider and in the upper arcuate portion of the segment. In Figures 2, 3, 5 to 8 and 12, the medial part of the arcuate segment is toward the outer side wall of the glider and held by the anchoring means thereat. In Figure 13 the medial part of the segment is toward the inner side wall of the glider and held by anchoring means carried by said inner wall and projecting into a medial part of said segment. In Fig. 10, the medial part of the segment is omitted, and only upper and lower arcuate sections 48', 48" utilized. While both of these sections may be anchored, if desired, it will ordinarily suffice to anchor only one to cause the assembly to travel with the glider, since compression and friction of the resilient member will retain the other or lower section in place. In all constructions shown, the annulus 47 may be of any suitable resilient material, of which rubber and neoprene are satisfactory examples.

In order that lubricant may be retained in the glider tubes, the ends thereof may be sealed by suitable caps 49 inserted and held in the outer ends thereof and fitting around the end margins of the bushings. The entire space from one bearing assembly to the other, around the rail and within the glider tube, see Fig. 3, may be filled with lubricant. Where a structure prevails, such as in Fig. 9 wherein the glider is more or less open, an encompassing sleeve 56 may be provided coaxial to and around the rail from one bearing assembly to the other. Such sleeve is larger than the rail so as to provide space therebetween for lubricant. One convenient arrangement is to use a sleeve of appropriate inside diameter so that its end margins may overlap and be carried by the contiguous end margins of bushings 46 with adequate fit to prevent leakage of the lubricant thereat.

In addition to their function as mounting means for the bearing assemblies 45, the glider formation is of a character which provides side walls in vertical planes, that is, planes perpendicular to the general top plane of the carriage, so as to provide reenforcement to resist tendency of the load to make the carriage sag. Where square tubing is utilized for the gliders, the utilization of a continuation of the material forming the gliders to also constitute a top plate as above described with respect to Fig. 9 is of course impossible. As best shown in Figs. 2 and 4, a top plate 57 may be provided which extends across from glider to glider and coextensive with the length of the gliders and overlapping the entire top walls of both gliders so that both side walls of both gliders

underlie said plate longitudinally thereof and are perpendicular thereto. The side edges of the plate are welded longitudinally to the upper edges of the side walls of the glider, as indicated at 58. If preferred, said top plate may be sectional, as best illustrated by Figs. 7 and 10, so as to provide one section thereof at the front end of the carriage and another section at the rear end of the carriage, each section being welded to the glider as above described. Furthermore, as shown in Fig. 10, said top plate may have abutting relation at its side edges with the two gliders, instead of overlapping the tops thereof. The welding of the side edges of the top plate unifies said plate with said gliders so that the reenforcement of the side walls of the gliders will be effective with respect to said plate. Thus, in all structures shown, the side walls of the gliders, perpendicular to the top plate, function as reenforcing beams for said top plate and assist in supporting the load which is applied to said plate.

Between said gliders, parallel thereto, and illustrated as approximately as long as said gliders, is a tubular housing 59, welded to and functioning as a beam reenforcement for said plate, said housing likewise preferably being rectangular and shown as square in cross-section. Longitudinally within said housing is a threaded shaft 60 which preferably projects from both ends of the housing and through the cleats 38 for rotational support thereby. The axis of said shaft and the geometric center line of the housing are substantially coincident. There is space within the housing, between it and said shaft, to receive a nut 61 which may be fed along the shaft by rotation of said shaft. The periphery of the nut 61 conforms to and is juxtaposed to the inner circumferential contour of the housing so as to keep the nut from rotating but enabling it to slide within the housing. As herein shown, a crank 62 is located and pinned on one end of the shaft where protruding through one cleat, thereby enabling the shaft to be conveniently rotated. A nut 63 is pinned or otherwise held on the shaft at the outside face of the other cleat, cooperating with said crank to prevent longitudinal movement of said shaft.

Where use of the support requires spring loading for the carriage, a spring 64 is provided with its convolutions encircling the shaft within the space between the shaft and housing. Rotation of the crank in one direction will draw nut 61 in a direction toward two pins 65 and compress the spring for applying tightening tension on belt 32. Rotation in the other direction impresses nut 61 against pins 66 traversing the housing on the far side of the nut from said spring, said pins being located in holes for the purpose in said housing.

Where use of the support requires positive actuation of the carriage, rather than spring loading, the nut 61 may be held from longitudinal displacement in the housing so that rotation of the crank not only moves the nut along the shaft, but necessitates that the carriage be correspondingly moved. Retention of the nut is obtained by other pins (not shown) in holes 69 at the other face of the nut from and functioning in conjunction with said pins 66 to confine the nut therebetween, said pins being located in close proximity respectively to the front and back faces of the nut. For this type of operation, no spring is required and may be omitted in accordance with the showing in Fig. 7.

Where a plurality of shafts, with accompanying springs, nuts, housings and pins are deemed desirable, as in Fig. 8, said shafts are interconnected for unison operation by chains and sprockets or equivalent means. Thereby all of the shafts will be rotated in unison, and as the respective nuts thereon are each prevented from turning by engagement in their respective housings they will be displaced simultaneously and equal amounts on and by their respective shafts. Where springs are used, each will be compressed a like amount. Where no springs are used, each nut will, with its shaft, take an equal share of the burden of moving the carriage.

In addition to and in conjunction with the longitudinal reenforcement of the top plate, I also provide a structure having cross-wise reenforcement. For instance, as shown in Figs. 6 and 7, diagonal braces 70 may be provided from the opposite bottom edges of housing 59 sloping upwardly outward to the most proximate upper edge of the glider tube 40, with the braces welded at their respective ends to said housing and tubes. The resultant structure constitutes a truss which will prevent any sag transversely in the carriage. I may use a single piece of material from glider to glider, dipping beneath the housing to constitute said braces, if so desired, as shown in Fig. 8.

I claim:

1. A support for machinery and the like, comprising a carriage and a rail, said carriage having a glider slidable with respect to said rail, and a bearing assembly interposed between said rail and glider, said bearing assembly having sliding fit on said rail and lateral mobility in said glider enabling said assembly to be self-aligning coaxially on said rail.
2. A support for machinery and the like, comprising a carriage and a rail, said carriage having a glider slidable with respect to said rail, and a bearing assembly interposed between said rail and glider, said bearing assembly having a bushing slidably fitting said rail and having an arcuate segment engaging said glider within the same.
3. A support for machinery and the like, comprising a carriage and a rail, said carriage having a glider slidable with respect to said rail, and a bearing assembly interposed between said rail and glider, said bearing assembly having a bushing slidably fitting said rail and having an arcuate segment engaging said glider within the same and a resilient member between said bushing and segment.
4. A support for machinery and the like, comprising a carriage and a rail, said carriage having a glider slidable with respect to said rail, said glider being substantially square in cross-section, and a bearing assembly interposed between said rail and glider, said assembly having an exterior arcuate member extending more than 180° around said assembly, said glider making tangential engagement with said member.
5. A support for machinery and the like, comprising a carriage and a rail, said carriage having a glider slidable with respect to said rail, said glider being substantially square in cross-section, and a bearing assembly interposed between said rail and glider, said assembly having an exterior arcuate C-shaped member, and each of a plurality of the walls of said glider making tangential engagement with said member.
6. A support for machinery and the like, comprising a carriage and a rail, said carriage having a glider slidable with respect to said rail, said glider being substantially square in cross-section, and a bearing assembly interposed between said rail and glider, said assembly having a bushing slidably fitting said rail and having an exterior C-shaped arcuate segment extending more than 180° around said bushing and adapted to make tangential engagement with a plurality of the walls of said glider, and said assembly having a resilient annulus between said bushing and segment with a part of said annulus exposed through the open side of said segment.
7. A support comprising a longitudinal rail, two aligned sleeves on and in slidable engagement with said rail and concentric therewith, a resilient tube substantially concentric with and upon each of said sleeves, an arcuate C-shaped member of more than 180° and less than 360° located substantially concentrically upon each said tube and having a compressional pre-loading engagement therewith, a rail-receiving means at least partially encompassing said sleeves and tubes and in tangential engagement with said C-shaped member, and a carriage body comprising a fixed part with said rail-receiving means and movable with said sleeve, tube and member on said rail.
8. A support comprising a longitudinal rail, a carriage body mounted to move longitudinally of said rail, said

body having side margin rail-receiving means at least partially encompassing said rail, a sleeve on said rail in sliding contact therewith, said sleeve being at least in part within said rail-receiving means, the outer surface of said sleeve having a straight-line configuration longitudinally thereof parallel to the surface of said rail, and said sleeve in its entirety encompassing said rail for a part of the length of said rail, a resilient tube having an inner surface in engagement with said outer surface of said sleeve, a C-shaped member encompassing said tube for more than 180° and compressing said tube with a part of said tube bulging from said C-shaped member,

whereby engagement between said means and member and between said means and bulging part of said tube permits self-alignment of said sleeve coaxially on said rail.
